RADAR SCANNER ANTENNA FEED

Tomlinson I. Moseley, Atherton, Calif.

Application August 27, 1946, Serial No. 693,194

1 Claim. (Cl. 250—33.63)

1

This invention relates, in general, to an antenna feed horn for radar scanners.

By the use of a directional antenna in conjunction with a reradiating metallic surface, it is possible to control the width, direction, and concentration of a radio frequency beam. Although the metallic surface may take the form of a flat plate, cylindrical section or paraboloid, the radiation pattern of the antenna feed must be adjusted with respect to the particular form of reflector used.

Antenna feed units in current use include a stem or section of forwardly tapering metallic tubing of rectangular cross-section provided at its rear end with a base member for securing the stem to its reflector and connecting it with the adjacent section of the wave-guide transmission line. Soldered or otherwise fastened to the forward end of the stem is a fixed ring formed with diametrically opposed, elongated and symmetrical windows for the passage of the radio frequency energy. Slidably mounted on the stem rearwardly of the fixed ring is an exteriorly threaded clamping ring, a mica window ring and two or more flat rings made of gasket material, each of these latter rings being provided with diametrically opposed windows arranged to register with the windows formed in the fixed ring. Disposed over the outer face of the fixed ring is a neoprene sealing ring and enclosing all of these rings is an antenna feed cap threaded to the clamping ring and forming an air-tight structure therewith. An air-tight structure is required for the reason that uniform operation depends upon maintaining the antenna feed and wave-guide transmission system at a constant pressure irrespective of the atmospheric pressure external thereto.

Electrical reflections within the wave-guide system result from irregularities in its various joints and to the practical difficulty of controlling its dimensions. Since these reflections travel in a direction opposite to the direction of electrical flow, they produce "standing waves" which nullify a portion of the initial radio frequency wave and materially decrease the power delivered at the output. Standing waves are also set up within the wave-guide system at transition sections (transformers) and, due to bends therein, the magnitude of the standing wave ratio produced from this latter source varies inversely as the radius of curvature of the bend.

Electrically the antenna feed is matched to its wave-guide transmission system or line by varying the depth, diameter and interior dimensions

2

of the antenna feed cap. However, this method of matching is unsatisfactory for it is dependent on having available a considerable number of feed caps of various depths and other dimensions, and matching simply by trying various caps.

Furthermore, considerable difficulty is encountered with this type of antenna feed due to voltage breakdowns resulting from the small clearance between the top of the feed cap and the fixed ring after matching and due to the fact the mid-points of the opposed edges of the feed stem are points of maximum voltage.

In general, the objects of this invention are two-fold; first, the provision of an antenna feed having a streamlined interior serving as a wave guide and which minimizes the formation of standing waves; and, second, the provision of an antenna feed including a feed cap which can be readily matched with its associated wave-guide system.

More specifically, the objects of this invention include the provision of an antenna feed wherein the outer ends of the opposed side walls of the feed stem are rearwardly curved and the inner surface of the feed cap has an arcuate contour so as to form with the rearwardly curved portions of the side walls a relatively smooth reversely curved wave guide.

Another object of this invention is the provision of an antenna feed having a stem twisted through ninety degrees so as, in effect, to change the polarity of the radio frequency energy passing through the wave-guide system of an associated radar scanner.

Still another object of this invention is the provision of a method for effecting a bond between the glass windows of the feed horn and the cap and stem of the feed horn.

The invention possesses other advantageous features, some of which with the foregoing will be set forth at length in the following description where those forms of the invention, which have been selected for illustration in the drawings accompanying and forming a part of the present specification, are outlined in full. In said drawings, two forms of the invention are shown, but it is to be understood that it is not limited to such forms, since the invention, as set forth in the claims, may be embodied in a plurality of forms.

Referring to the drawings:

Fig. 1 is a perspective view of a radar antenna feed embodying the objects of my invention.

Fig. 2 is an exploded view of the outer end of the antenna feed illustrated in Fig. 1.

Fig. 3 is a perspective view of a longitudinal section of the outer end of the antenna feed shown in Figs. 1 and 2.

Fig. 4 is a top-plan view, partly in section, of a modification of the antenna feed illustrated in Figs. 1, 2 and 3.

Fig. 5 is an exploded view of the rear or forward end of the feed illustrated in Fig. 4.

The antenna feed illustrated in Figs. 1, 2 and 3 includes a forwardly tapered hollow steel wave-guide stem 1 of rectangular cross-section, the long dimension of the section being in a vertical plane so that the radio frequency energy passing therethrough will vibrate in a vertical plane.

Soldered or otherwise fastened to the base of the stem 1 is a circular base plate 2 provided with screw holes 3 by which it can be fastened to a suitable paraboloid reflector and to the wave-guide system forming a part of the scanner unit. As shown in Fig. 1, the base plate 2 is provided with a central rectangular opening 4 arranged to form a continuation of the rectangular stem conduit.

The opposed side walls 5 and 6 of the stem 1 extend forwardly beyond its top and bottom walls and are curled rearwardly and uniformly to form diametrically opposed window supports.

Soldered to and over the outer or forward ends of the top and bottom of the stem 1 is a steel die-stamped antenna cap 7 formed with rearwardly inclined side walls 8 and 9 and with a circular rim 11. Soldered over and to the rear face of the rim 11 and to the stem walls 5 and 6 is a pair of diametrically opposed and generally semicircular windows 12 and 13 made of low-loss Pyrex glass. However, prior to securing the windows 12 and 13 in place, the interior surfaces of the stem and its cap are silver-plated and palladium-flashed so as to make them good conductors.

In order to fasten and seal windows 12 and 13 to the cap 7 and the stem 1 so that they will withstand fifteen pounds of air pressure, it has been found desirable to go through the following procedure:

The outside edges of the window are painted with a Hanovia silver paste which deposits a thin layer of silver on to the edge. The entire window is then baked to a temperature of 600° C. and then cooled at a predetermined rate to 300° C. after which it is removed from the oven and allowed to cool to room temperature. The baking procedure attaches the silver deposit firmly on to the glass edge so that it will not peel. After the windows have cooled to room temperature they are given a copper plate. The copper naturally only sticks to the silver coated edges. The copper plated edges are now tinned in preparation for soldering to the feed cap edge. The entire feed horn cap and assembly is now heated to a specific temperature and the windows placed thereon with their matching surfaces lined up. The specific temperature aforementioned is such that it keeps the tinned surface of the window molten. Upon the removal of the heating source the solder cools and forms a pressurized bond between the tinned window and its mating antenna cap surface.

A comparison of this method of attaching windows for pressurization purposes, to the standard practices used in the trade, indicates that the present method results in a feed horn having a longer life and one which is more con-

sistently perfect, and forms a better pressurized joint.

Threaded to the cap 7 in alignment with the axis of the stem 1 is a short-tuning screw or button 14 by which the antenna feed is matched electrically to the wave-guide system or feeder transmission line with which it is designed to be associated. After the required matching has been effected by the tuning button, it is soldered to the feed cap in its adjusted position.

The antenna feed shown in Figs. 4 and 5 includes a forwardly tapered stem 21, rectangular in cross-section and twisted through an angle of 90°. As in the case of the feed illustrated in Figs. 1, 2 and 3, the opposed side walls 22 and 23 of the stem are convergent so as to form a gradually tapered stem and the forward portions of these walls are reversely curved as at 24 and 25. Soldered or otherwise secured to the forward edges 26 and 27 of the top and bottom walls of the stem is a feed cap having an arcuate inner surface 29 substantially complementary to the curved surfaces of the side walls 22 and 23 and forming therewith a pair of diametrically opposed wave guides 31 and 32. Sealed to the outer ends of the walls 22 and 23 and to the peripheral rear edge of the cap 28 is a pair of semicircular low-loss Pyrex glass windows 33 and 34. The method of fastening and sealing these windows is the same as set forth with respect to the modification shown in Figs. 1, 2 and 3. Threaded through the cap 28 is an adjustable tuning button 35 by which the antenna feed can be matched with its associated wave-guide system or transmission line.

Secured to the base of the stem 21 is a circular base plate 36 by which the stem is secured to its reflector and connected with the wave-guide system of its associated scanner unit.

From the above description it will be noted that I have provided an externally tunable antenna feed horn of very simple construction requiring for its manufacture only six parts, a base plate, a stem, a one-piece feed cap, a pair of glass windows, a tuning button, and a very effective method of sealing these windows in place. Due to the rearwardly directed wave guides formed by the curved ends of the stem, side walls and the interior surface of the feed cap, the radio frequency beam is reflected rearwardly to the reflector with a minimum formation of standing waves. Matching of an antenna feed of this type with its associated wave-guide system is effected by simply adjusting the tuning button and then soldering it in its adjusted position. In this connection, it is to be noted that the matching of this type of feed and the design of its cap depends upon the thickness of the windows. They should be of sufficient thickness to increase the distance between the tuning button and its closest contact point. Such a design further avoids the high power breakdown troubles now encountered in standard antennas.

Although dimensions of antenna feeds of this type are critical and must be correlated to the radar scanner of which they form a part, the design herein disclosed is applicable to any antenna feed regardless of the specific dimensions required and which can only be determined by trial and error.

I claim:

An antenna feed horn comprising a tubular stem of rectangular cross section having side walls and top and bottom walls, said side walls extending at one end beyond the top and bottom

walls and being reversely curved, a cup-shaped cap stamped from an integral sheet of material and having a bottom, side walls diverging from the bottom and a circular rim, said bottom being formed with a central opening to receive a tuning button, a tuning button received within said opening, and a window formed of two curvilinear sections of glass having the same radius as said rim and adapted to seat behind said reversely curved portions of the side walls and adjacent 10 said rim, said glass sections being bonded to said stem and cap and serving to mount the cap on the stem.

TOMLINSON I. MOSELEY.
